UNITED STATES PATENT OFFICE.

ALFRED LESCHKA AND ADOLF FIALA, OF NEW YORK, N. Y.

DOOR-CHECK.

1,169,841.

Specification of Letters Patent.

Patented Feb. 1, 1916.

Application filed June 2, 1915. Serial No. 31,686.

To all whom it may concern:

Be it known that we, ALFRED LESCHKA and ADOLF FIALA, subjects of the Emperor of Austria-Hungary, and residents of the 5 city of New York, in the counties of Bronx and New York, respectively, and State of New York, have invented certain new and useful Improvements in Door-Checks, of which the following is a specification.

10 The present invention relates to a door check, and has for one of its objects to provide a simple and inexpensive device of this type which, when in a certain position, allows the door to be opened to a certain 15 extent, and which, when in another position, serves to lock effectively the door to prevent the same from being opened even to a slight extent.

Another object of the invention is to produce a device of this type, the locking means 20 of which can also be actuated by a key from the outside.

With these and other objects in view, which will more fully appear as the nature 25 of the invention is better understood, the same consists in the combination, arrangement and construction of parts hereinafter fully described, pointed out in the appended claims and illustrated in the accompanying 30 drawings, it being understood that many changes may be made in the size and proportion of the several parts and details of construction within the scope of the appended claims without departing from the spirit 35 or sacrificing any of the advantages of the invention.

One of the many possible embodiments of the invention is illustrated in the accompanying drawings, in which:—

40 Figure 1 is a front elevation of a portion of a door and door frame to which a door check constructed in accordance with the present invention is applied, the parts being in position to hold the door closed; Fig. 2 is a section taken on line 2—2 of Fig. 1; Fig. 3 is a front elevation of a door and door frame and the device mounted thereon, showing the door opened to some extent; Fig. 4 is a section taken on line 4—4 of Fig. 50 3; Fig. 5 is a rear elevation of one element of the door check; Fig. 6 is a side elevation thereof; Fig. 7 is a view similar to that shown in Fig. 5 with the closing plate removed in order to more clearly show the interior construction; Fig. 8 is a section taken on line 8—8 of Fig. 7; Fig. 9 is a section 55

taken on line 9—9 of Fig. 7; Fig. 10 is a section taken on line 10—10 of Fig. 7; Fig. 11 is a front elevation of the link of the door check and the base to which it is attached; 60 and Fig. 12 is a section taken on line 12—12 of Fig. 11.

Generally speaking, the invention relates to that type of door checks which comprise a link carried by the door jamb, in combination with locking means mounted upon the 65 door.

Referring now more particularly to the drawings, the numeral 20 designates a portion of a door jamb, and 21 indicates a portion of a door. To the door is attached by screws 22, or otherwise, a lock casing 23, in the front end-wall 24 of which is provided an opening 25, merging into an aperture 26 in the front plate 27 thereof. With the 70 end-wall 24 is made integral an outwardly extending projection 28, having an aperture 29, that forms, as it were, a continuation of the opening 25, and extends a suitable distance beyond the outer face of the front 75 plate 27, as clearly shown in Fig. 8 of the drawings. Within the lock casing is disposed a sliding bolt 30, made of two sections 31 and 32, which are guided in their movements by ledges 33 formed within the 80 lock casing. The sections of the bolt are connected by a lug 34, preferably, made integral with the section 31 and projecting into a slot 35 in the section 32. Owing to 85 this arrangement, the section 31 of the bolt 90 can be retracted without causing a movement of the section 32 thereof. However, if the latter is retracted in a manner hereinafter described, the section 31 will be caused to move therewith. The purpose of this 95 arrangement will be described hereinafter. The section 31 of the bolt is under the action of springs 36 which are coiled upon stationary pins 37, and bear against the rear ledges 33 and an enlargement 38 upon the 100 section 31 of the sliding bolt. These springs project the bolt, causing the front portion of the section 31 thereof to overlie partly the aperture 26 in the front plate 27 of the casing, or in other words to restrict the said 105 aperture.

The section 32 of the bolt carries a lug 39, that is substantially hook-shaped, as clearly shown in Fig. 8 of the drawings, said lug projecting through a longitudinal slot 40 in 110 the front plate of the lock casing. This lug serves, among other purposes, as the

means by which the sliding bolt can be manually retracted. The sliding bolt can be actuated also by a key from the outside. The bit of the key is adapted to engage a 5 suitably shaped groove 41 in a turning spindle 42, said spindle extending into the slot 35 above described and being provided with arms 47, which are adapted to engage with shoulders 48 on the bolt section 32. This 10 turning spindle extends at the same time into an aperture 49 in a cover plate 50, which can be held upon the lock casing in any suitable manner, for instance its reduced rear end 51 may reach under a shoulder 52 on the said lock casing, while its 15 front end is engaged by a keeper 52', that is pivoted at 53 to one of the ledges 33.

The sliding bolt can be locked in its projected position by a catch 54, said catch being rigidly attached to a knob 55, that is 20 oscillatably mounted upon the front plate of the lock casing. This catch is adapted to abut against a shoulder 55' upon the bolt section 31.

25 To the door jamb is secured a base plate 56, the latter being disposed within a suitably shaped mortise in said jamb, and has pivoted thereto at 57 a link 58, provided at its free end with a head 59. A longitudinal 30 slot 60 is formed in the link, and through this slot is adapted to extend the hook-shaped lug 39.

The operation of this device is as follows: In use the sliding bolt is retracted by means 35 of the lug 39, which will permit the head 59 of the link 58 to be passed through the apertures 29 and 26 in the projection 28 and the front plate 27, respectively. After 40 this the lug 39 is released, and the door fully closed, by which operation the lug is inserted 45 into the slot 60 in the link, and the head 59 of the link caused to abut against the rear end-wall of the lock casing. The shoulder 39' of the lug 39 overlaps thus the link 58. 50 If now the catch 54 is turned so that it contacts with the shoulder 55' of the bolt section 31, the sliding bolt is held permanently 55 retracted and the door securely locked. As long as the catch is in this position, it is impossible to open the door by use of a key from the outside. From the inside, obviously, the door can be easily opened by 60 swinging the catch into the position shown in full lines in Fig. 7 of the drawings, and by retracting the locking bolt in the usual manner.

If it is intended to open the door to a limited extent for ventilation or for some other purpose, first the catch 54 is swung into position shown in full lines in Figs. 5 and 7. After this the locking bolt is retracted and the link disengaged from the lug 39, and, finally, the catch is swung into the position shown in dotted lines in Fig. 7 of the drawings. The front portion of the bolt section

31 overlies then partly the aperture 26 in the front plate of the lock casing. When the parts are in these positions, the link head 59 cannot pass through the apertures 26 and 29. The door can now be opened to a limited extent, that is to say until the head of the link comes into contact with the front portion of the bolt section 31.

If it is intended to permit the door to be 75 opened by means of a key, the catch is swung to its position shown in full lines in Fig. 7 of the drawings. By turning the spindle 42 by a key in one or the other direction, its arms 47 will engage with one or the other shoulder 48 of the section 32 of the sliding bolt and retract both bolt sections. The bolt is then held in retracted position and the door forced inward, whereby the link 58 will disengage itself from the lug 39 and slide through the apertures 29 and 26. 80 85

It is to be observed that, while herein the lock casing has been described as carried by the door and the link by the door jamb, the positions of these parts may be reversed.

The sliding bolt is made of two sections 90 for the reason that if, in trying to pick the lock, the section 31 of the bolt is retracted by a bladed instrument or similar contrivance, the lug 39 will still be held in engagement with the link and thereby prevent an opening of the door. 95

What we claim is:—

1. The combination with a door and door jamb, of a base plate fastened to one of said members, a link pivoted to said plate 100 having a head upon its free end, a casing attached to the other one of said members having an outwardly extending projection, said projection being provided with an aperture in alinement with and forming a continuation of an aperture in the front plate of said casing, a sliding bolt within said casing made of two sections, the front section of said bolt obstructing in its projected position the aperture in the front plate of said 105 casing, said front section being adapted to slide independently of the rear section of the bolt but the retracting of the latter withdrawing also said front section, the head of said link being adapted to pass through said 110 apertures when the locking bolt is retracted, means upon said rear section for manually actuating said sliding bolt, means engaging said rear section adapted to be actuated by a key for retracting said bolt from outside, 115 and a catch for holding said sliding bolt in its retracted position. 120

2. The combination with a door and door jamb, of a base plate fastened to one of said members, a link pivoted to said plate having a head upon its free end, a casing attached to the other one of said members having an outwardly extending projection, said projection being provided with an aperture in alinement with and forming a con- 130

tinuation of an aperture in the front plate of said casing, a sliding bolt within said casing made of two sections, the front section of said bolt obstructing in its projected

5 position the aperture in the front plate of said casing, said front section being adapted to slide independently of the rear section of the bolt but the retracting of the latter withdrawing also said front section, the head 10 of said link being adapted to pass through said apertures when the sliding bolt is retracted, and means upon said rear section for manually actuating said sliding bolt.

3. The combination with a door and door 15 jamb, of a base plate fastened to one of said members, a slotted link pivoted to said plate having a head upon its free end, a casing attached to the other one of said members having an outwardly extending projection,

20 said projection being provided with an aperture in alinement with and forming a continuation of an aperture in the front plate of said casing, a sliding bolt within said casing obstructing in its projected position

25 the aperture in the front plate of said casing, the head of said link being adapted to pass through said apertures when the locking bolt is retracted, a lug carried by said bolt projecting through a slot in the

30 front plate of said casing, said lug being adapted to be seated in the slot in said link and serving also as the means by which the sliding bolt can be manually retracted, and a catch for holding said sliding bolt in its

35 retracted position.

4. The combination with a door and door jamb, of a base plate fastened to one of said members, a slotted link pivoted to said plate having a head upon its free end, a 40 casing attached to the other one of said members having an outwardly extending projection, said projection being provided with an aperture in alinement with and forming a continuation of an aperture in

the front plate of said casing, a sliding bolt 45 within said casing obstructing in its projected position the aperture in the front plate of said casing, the head of said link being adapted to pass through said apertures when the sliding bolt is retracted, and 50 a lug carried by said bolt projecting through a slot in the front plate of said casing, said lug being adapted to be seated in the slot in said link and serving also as the means by which the sliding bolt can be manually retracted.

5. The combination with a lock casing having an aperture, a sliding bolt within said casing made of two sections, the front section of said bolt obstructing in its projected position the aperture in said casing, said front section being adapted to slide independently of the rear section of the bolt but the retracting of the latter withdrawing also said front section, means upon said 65 rear section for manually actuating said sliding bolt, and means engaging said rear section adapted to be actuated by a key for retracting said bolt from outside.

6. The combination with a lock casing 70 having an aperture, a sliding bolt within said casing made of two sections, the front section of said bolt obstructing in its projected position the aperture in said casing, said front section being adapted to slide 75 independently of the rear section of the bolt but the retracting of the latter withdrawing also said front section, and means upon said rear section for manually actuating said sliding bolt.

Signed at New York, in the county of New York, and State of New York, this 24th day of May, A. D. 1915.
